233,862

BLOOD CELL ANALYZER OR SIMILAR ARTICLE

John Russell Nelson, Natick, Mass., David Edward Roche, Nashua, N.H., and Joseph John Montagna, Acton, Mass., assignors to Coulter Electronics Inc., Hialeah, Fla.

Filed Oct. 18, 1973, Ser. No. 407,535

Term of patent 14 years

Int. Cl. D24—01

U.S. Cl. D83—1 F

The single figure is a perspective view of the front, top and one side of a blood cell analyzer or similar article of our new design;

The side not shown is identical to the side shown in the single figure;

The rear comprises two unadorned planar surfaces extending from the top and bottom respectively and substantially perpendicular to the top and bottom;

The bottom extends in a plane parallel to the top and is unadorned.

We claim:

The ornamental design for a blood cell analyzer or similar article, substantially as shown and described.
